FOLD-AWAY WALL MOUNTED DINING TABLE OR SIMILAR ARTICLE

Nicholas A. Ungaro, Louisville, Ky., assignor to Kroehler
Mfg. Co., Naperville, Ill., a corporation of Illinois

Filed Apr. 28, 1960, Ser. No. 60,353

Term of patent 14 years

(Cl. D33—14)

FIG. 1 is a front perspective view of a fold-away wall mounted dining table or similar article in extended position, showing my new design, and

FIG. 2 is a similar view thereof, but showing my new design in folded position.

The side of my fold-away wall mounted dining table or similar article opposite that shown in FIGS. 1 and 2 is identical.

The characteristic features of my design reside in the portion shown in full lines and consists of a wall-mounted drop-leaf table having an extensible top and bevelled leg member which in closed position rests within the rectangular wall supported frame. The foldable leg is pivotally connected to one end of the table top and when closed,

same complements the lower peripheral moulding of the top to convey a picture frame effect, as shown.

The dotted line indication of a wall in FIGURE 1 is for illustrative purposes only.

I claim:

The ornamental design for a fold-away wall mounted dining table or similar article, as shown and described.
